UNITED STATES PATENT OFFICE.

ALBERT E. SUITER, OF LOCKHAVEN, PENNSYLVANIA.

ROTARY STEAM-ENGINE.

SPECIFICATION forming part of Letters Patent No. 759,571, dated May 10, 1904.

Application filed September 18, 1903. Serial No. 173,711. (No model.)

To all whom it may concern:

Be it known that I, ALBERT E. SUITER, a citizen of the United States, residing at Lockhaven, in the county of Clinton and State of Pennsylvania, have invented a new and useful 5 Rotary Steam-Engine, of which the following is a specification.

My invention relates to rotary engines, and comprises in its most comprehensive form the 10 compound rotary engine hereinafter fully described, shown in the accompanying drawings, and having the novel features thereof pointed out in the appended claims.

One object of the invention is to produce an 15 exceedingly compact, powerful, and economical steam engine or motor susceptible of high speed, in which all clearance is completely abolished and the full pressure and expansion of steam are utilized to their full limit in imparting mechanical energy to the revolving piston.

Another object of the invention is to use the 20 exhaust-steam in the production of mechanical forces and finally as a generator of heat to prevent condensation of live steam.

A further object of the invention is to produce such combinations of steam-chests, cylinders, and steam-ports that the current of live steam passes directly from the steam-chests to 25 the expansion-chests without loss of energy by diminution of temperature or friction.

A further object is to produce an engine in which all the working parts have rotary movement and are timed to act in unison.

30 A further object is to provide a centrifugal governor for controlling the point of cut-off for the steam entering the expansion-chambers according to the amount of load on the engine.

40 A further object is to provide metallic packing devices for the journals, shafting, and revolving pistons and abutment-valves which are adapted to expand automatically to offset any wear of the packing, so that until the 45 jacking is practically worn completely away it will maintain steam-tight joints.

A further object is to provide a combination of valves and operating-levers therefor whereby both cylinders of the engine may be 50 employed as high-pressure cylinders or either

cylinder may be used independently of the other, and whereby the engine may be reversed.

A further object is to place the exhaust-ports of the high-pressure cylinder in a direct line 55 with the inlet-points of the low-pressure cylinder, thus preventing loss of power in the transmission of steam from the high-pressure to the low-pressure cylinder.

In the drawings, Figure 1 is a view, chiefly 60 in side elevation and partly in section, of a compound rotary engine constructed in accord with my invention, certain parts being omitted for the sake of clearness. Fig. 2 is a transverse section through the high-pressure cylinder of the engine shown in Fig. 1. Fig. 3 is a view in longitudinal section through the cylinders, governor, and valve-operating mechanism of a compound rotary engine similar to that shown in Fig. 1, but with a somewhat 65 different form of governor. Fig. 4 is a vertical transverse section through the high-pressure steam-chest of the engine shown in Fig. 1. Fig. 5 is a detail view of one of the valve-disks for controlling the entrance of steam 70 into the engine-cylinders. Fig. 6 is a detail view of the counter-disk co-operating with the valve-disk shown in Fig. 5. Fig. 7 is a view in elevation of the governor shown in Fig. 3, the view being taken from the front. Fig. 8 75 is a diagrammatic view to illustrate the action of the abutment-valves in permitting the passage of the piston-blades through them. Fig. 9 is an end elevation of the mechanism for adjusting the time of movement of the abutment-valves, the view being taken from the front. Fig. 10 is a detail view showing the packing of one of the abutment-shafts. Fig. 11 is a detail showing the packing members 80 used on the abutment-valve wings and piston-blades. Fig. 12 is a detail view showing the form of one end of a piston-blade. Fig. 13 is a detail view in section, showing the packing members as illustrated in Fig. 11 applied to a piston-blade or abutment-wing. 85 Fig. 14 is a detail in elevation of one side of the piston-blade, showing a special form of packing. Fig. 15 is a view similar to Fig. 14, showing a somewhat different form of packing. Fig. 16 is a detail view in section 90

through a piston-blade, showing the relation of the steam-ring and packing members. Fig. 17 is a detail view showing in plan a part of the mechanism for reversing the action of the 5 governor shown in Fig. 1. Fig. 18 is a detail view from the back of a part of the mechanism for reversing the action of the governor shown in Fig. 1. Fig. 19 is a detail view of the rack formed on operating-rod 88 and the 10 segmental gear which meshes therewith. Fig. 20 is a view in horizontal longitudinal section through a simple rotary engine constructed in accord with my invention, certain parts being omitted for the sake of clearness. Fig. 15 21 is a cross-section in vertical plane through the cylinder of the engine shown in Fig. 20. In all the figures corresponding parts are 20 designated by the same characters of reference.

20 Referring to the drawings in detail, 1 represents a base-plate to which the engine is bolted.

25 2 designates a high-pressure cylinder, 3 a low-pressure cylinder, and 4 a main shaft passing through both cylinders and carrying belt-pulleys 5, Fig. 3. Both cylinders are provided with channels in the walls thereof, as shown, to permit the circulation of exhaust-steam in order to prevent condensation of steam 30 in the expansion-chambers of said cylinders. The high-pressure and low-pressure cylinders are substantially alike in design, though certain minor differences will be hereinafter pointed out. The high-pressure cylinder 35 (shown in cross-section in Fig. 2) has in common with the low-pressure cylinder, expansion-chambers 7, and on either side thereof, and communicating therewith are smaller cylindrical chambers 8, in which are mounted 40 abutment-valves. The expansion-chambers 7 contain a rotary piston mounted on the shaft 4 and having a hub 9, from which project three piston-blades 10, both the hub and piston-blades being provided with suitable packing devices, which will be hereinafter described. 45 The piston-blades 10 are curved convexly on either side, as shown, and the curvature is the same as that of the wall of the expansion-chambers 7, the utility of which form will 50 afterward be shown. Extending longitudinally through the chambers 8, containing the abutment-valves, are shafts 11, which also extend through similar chambers adjacent to the expansion-chambers in the low-pressure 55 cylinder. The abutment-valves each consist of a hub portion 11', having projecting therefrom three wings 12, spaced equidistant around the hub portion and being curved at their ends to correspond to the curvature of the chambers 8, in which they are mounted to 60 rotate, and having their sides concavely curved, so that when one of the abutments is in the position indicated in Fig. 2 at the left side the curvature of one of the wings will form a 65 continuation of the wall of an expansion-

chamber 7. At the point of juncture of two adjoining wings of an abutment-valve there is provided a groove extending longitudinally of the valve—that is to say, parallel to its axis—to provide the passages necessary for the 70 steam at certain times. It will be noted that as each of the wings of the abutment-valves has on either side a concave curve of the same radius as the expansion-chambers and each 75 of the blades 10 of the rotary piston has a convex curve on either side on the same radius it is possible for the piston-blades to contact completely with the wings of the abutment-valves when at certain points of their travel. Each of the wings of the abutment-valves is provided with packing devices, as shown, which will be hereinafter described in detail.

The steam-chests for both cylinders are placed between the high and low pressure cylinders, as best shown in Figs. 3 and 4, the low-pressure chest, whose outer wall is designated at 13, lying outside of and completely enveloping the high-pressure steam-chest, whose wall is designated at 14. The wall of the low-pressure steam-chest, like that of both cylinders, is channeled for the passage of exhaust-steam, as shown, for the purpose of utilizing what heat is contained in the exhaust-steam to keep up the temperature of the steam-chest wall, 90 thus preventing condensation within the chest. The valve for controlling the admission of the steam into the steam-chests is indicated at 15 and comprises the outer casing 16 and the inner partition 17, terminating at its upper 95 end in a chamber 18, to which steam is admitted at 18^a and in which is mounted to oscillate a valve proper, 19, of the form shown. On the right of the partition 17 and between it and the casing 16 is a passage 20 for the 100 transmission of steam to the low-pressure cylinder, said passage 20 opening through the side wall of the partition 17 into the chamber 18, as shown, and to the left of the partition 17 is a passage 21, similar to the passage 20 105 and leading to the high-pressure cylinder, the openings from the passages 20 and 21 into the chamber 18, it will be observed, being placed near the top of said chamber and separated by an arc of about one hundred and twenty 110 degrees. The valve proper, 19, which is oscillated by means of a lever 22, moving over a curved and slotted guide 23, is adapted when in the position indicated in Fig. 1 to admit steam directly to the high-pressure 115 steam-chest, from which it passes through ports, presently to be described, into the high-pressure cylinder and thence into the low-pressure steam-chest, from which it passes into the low-pressure cylinder. The passage 120 20, leading from the valve-chamber 18 to the low-pressure cylinder, is closed by the valve 19, as shown in Fig. 1, and consequently steam reaches the low-pressure cylinder only after it has passed through the high-pressure cyl- 125 130

inder. By raising the lever 22 until it is in horizontal position the valve 19 will be rocked sufficiently to open the passage leading from the valve-chamber 18 into the passage 20, but 5 will not close the passage 21, leading to the high-pressure steam-chest. Consequently with both passages receiving steam directly from the pipe leading from the boiler the pressure of the steam in both cylinders will 10 be the same, and the engine will have two high-pressure cylinders instead of being a compound engine. By raising the lever 22 to a point half-way between the horizontal position and the upper limit of its movement the valve 19 will be caused to close the 15 passage 21, leading to the high-pressure cylinder, and the passage 20, leading to the low-pressure cylinder, will be opened to permit the passage of steam directly to the low-pressure steam-chest and cylinder without passing through the high-pressure cylinder, thus cutting out the high-pressure cylinder entirely and using the cylinder which ordinarily serves as a low-pressure cylinder as a 25 high-pressure cylinder and driving the engine by means of that cylinder alone.

The passage of the steam from the high-pressure steam-chest into the high-pressure cylinder takes place through the ports 24 25, 30 provided on opposite sides of the main shaft 4 in the end plate 26 of the high-pressure cylinder, and the exhaust-ports from the high-pressure cylinder into the low-pressure steam-chest are designated at 27, 28, 29, and 30, as 35 best shown in Fig. 4.

The ports for the admission of steam to the low-pressure cylinder are disposed substantially opposite the ports 24 25 in the end plate 31 of the low-pressure cylinder, each port being therefore between a pair of exhaust-ports 40 from the high-pressure cylinder.

For controlling the admission of steam to the high-pressure cylinder through the ports 24 25 rotary valves are provided, as best shown in Figs. 3, 5, and 6. Each of the cylinders has the same kind of valve, the difference being merely one of size, and hence one description will suffice. Each of said valves consists of a main valve-disk 32, having a rim 33, a 45 hub 34, solid portions 35, and openings 36, the openings 36 and the solid portions 35 being of equal area and arranged alternately, as shown. The hub 34 is mounted on main shaft 4, as 50 best shown in Fig. 3, and the disk of the valve lies substantially in contact with the end plate of one of the cylinders, as is also seen in Fig. 3. The connection of the hub 34 of the valve-disk with the main shaft 4 is of the form shown in Fig. 5, comprising a key 37, provided on the shaft which engages the recess 38 in the hub of the valve-disk, the object of this form of connection being to permit movement of the valve-disk on the shaft, so that the valve may operate equally well when the

engine is driven in the customary direction 65 and when reversed.

Lying adjacent to each of the valve-disks 32 is a counter-disk 39, having a hub 40 loosely journaled on the shaft 4 and forming an envelop over the hub of the valve-disk 32, and 70 wings 41 of the same area as the solid portions 35 of the valve-disk 32. Normally the wings 41 of the counter-disk coincide in position with the solid portions 35 of the valve-disk, and the two disks rotate together. The valve-disks 75 are of course so mounted on the shaft 4 with relation to the pistons in the cylinders that the openings 36 of the valve-disk come over the steam-ports leading into the cylinders at the proper moment to drive the pistons without loss of power.

When a heavy load is on the engine, it is desirable for the period during which steam enters the cylinders from the steam-chests to be as long as possible in order to give as much direct boiler-pressure as possible to the blades of the piston; but when the load is light it is advantageous to shorten the period of direct boiler-pressure and increase the length of the period of expansion of steam in the cylinders. 90 This is provided for in the arrangement of valve-disks and counter-disks already described, together with the governor of either form shown in Fig. 1 or Fig. 3. The form shown in Fig. 3 is the preferred form and 95 comprises the following parts: Extending through the shaft 4 from the high-pressure steam-chest to the belt-pulley 5 in a channel provided for that purpose is a governor-shaft 42, having a crank portion 43, which is attached, by means of a bolt, as shown, to a lug on the hub 40 of the counter-disk 39 and to a sleeve 43^a, which is securely attached to the hub of the counter-disk of the valve of the low-pressure cylinder, as clearly shown in 100 Fig. 3. At the other end the governor-shaft is provided with a stuffing-box 44, fitted into the end of the main driving-shaft 4, and has rigidly attached thereto an arm 45, extending to either side of the shaft 42. Pivoted connected with the arm 45 at either end is a link 46, which is connected at its other end with a rock-lever 47, pivotally mounted upon a projection on the face of the belt-pulley 5 and having at one end a weight 48. In order to 115 hold the weights in the position shown in Fig. 7, springs 49 are provided of sufficient tension to hold the arms 47 against swinging outward under centrifugal force of the weights when the engine is going at moderate 120 speed; but when the speed increases above a certain predetermined rate for which the tension of the springs 49 is adjusted the centrifugal force of the weights 48 is sufficient to 125 swing the bars 47 on their pivots, and thereby communicate through the links 46 a rocking movement to the governor-shaft 42. The movement of the governor-shaft 42 is trans-

mitted through the crank 43 to the disk 39, which is loosely journaled on the shaft 4, and the counter-disk is moved ahead of the disk 32, so that the rings 40 of the counter-disk no longer coincide in position with the solid parts 35 of the valve-disk 32, but instead overlie portions of the openings 36, thus shortening the period of entry of the steam from the steam-chests into the cylinders. With high boiler-pressure and a light load on the engine the maximum speed of the pistons and shaft 4 will soon be developed, and when such is the case the weights 48 will swing outward under the influence of centrifugal force until they reach their limit of movement, and the governor-shaft 42 will be rocked so far in a forward direction that the rings 40 of the counter-disk will cover almost completely the openings 36 in the valve-disk 32, thus reducing almost to nothing the quantity of steam admitted to the cylinders, which will of course reduce the speed of the engine. With a heavy load upon the engine speed is not developed so rapidly and the centrifugal tendency of the weights 48 does not become sufficient to overcome the tension of the springs 49, so the governor-shaft 42 is not rocked, and the counter-disk 32 is not advanced to diminish the period of entry of steam into the cylinders.

It is vital in the successful operation of rotary engines that mechanism be provided for operating the abutment-valves at intervals so related to the movement of the piston-blades that the wings of the abutment-valves may be closed in quickly behind the piston-blades and may also move out of the way of approaching piston-blades at the right moment. If mechanism is not provided which effects the proper timing of the movements of the abutment-valves in relation to the movement of the piston-blades, pounding will result from the contact of the piston-blades with the wings of the abutment-valves, or there will be a loss of energy owing to the escape of steam around the ends of the piston-blades when passing through the valves.

One of the cardinal features of the present invention is the provision of means for operating the abutment-valves, which positively insures the proper timing of the movements of the valves and the piston-blades, which prevents pounding, which obviates the loss of energy by the escape of steam, and which permits adjustment of the valve-operating mechanism to compensate for wear of the abutment-wings or the piston-blades, or both.

In the operation of the abutment-valves in the engine forming the subject of this application the direct pressure of live steam is used to turn the abutment-valves through the greater portion of each movement thereof and mechanical means is employed only to produce the initial portion of each movement and

to prevent positively any backward movement of the abutment-valves from any cause.

In order to produce the initial portion of each movement of the abutment-valves, I provide on the main shaft 4 of the engine a disk 50, having adjustably mounted thereon at the center a member 51, comprising the circular portion 52 and three arms 53, having concavely-curved faces 54, which are arranged equidistant from each other at the periphery of the circular portion 52 and correspond in number to the blades of the piston, which in this instance is three. The member 51 is adjusted in position by means of a set-screw 55, passing through a curved slot 56, so that the member may be shifted forward in the direction of movement of the main shaft or in the opposite direction, as may be necessary.

Upon the shafts 11, upon which are mounted the abutment-valves, I provide the small disks 57, each of which has projecting from the face thereof which is directed toward the disk 50 a plurality of pins or bolts 58, each disk being provided with three pins or bolts to correspond to the number of wings of each abutment-valve. Upon the pins 58 are mounted freely-rotatable rollers 59, adapted for engagement with the arms 53 upon the member 51.

Spaced at equal distances around the disk 50 are recesses 60, the positions of which are indicated in Fig. 9. In each of the recesses 60 is adjustably mounted a segmental block 61, which is adjusted in position by means of a set-screw, as shown, and which has the inner face thereof cut away at the ends, as shown, to present rounded shoulders for engagement with the rollers 59 upon the pins 58.

The relative arrangement of the various parts in the mechanism described in the preceding paragraphs is illustrated best in Fig. 9, in which it is shown that the segmental blocks 61 lie substantially midway between the projections 53 and the pins 58, and rollers 59 are so placed on the disks 57 that the rollers may travel along the periphery of the circular portion 52 of member 51 and also roll along the concave faces of the blocks 61.

When Fig. 9 is compared with Fig. 8, which shows the piston-blades and abutment-wings in the position occupied thereby when the members shown in Fig. 9 are in the position indicated, it will be noted that the rollers 59 lie just slightly in advance of the forward faces adjacent abutment-wings and that the projecting arms 53 lie slightly behind the adjacent piston-blades.

The operation of the abutment-valves will be understood from a careful examination of Figs. 8 and 9 and Figs. 2 and 20.

Referring first to Figs. 8 and 9 it will be noted that steam is supposed to be entering the upper expansion-chamber of the engine-cylinder through the port 24 at the left of

Fig. 8, and consequently the steam acts equally upon the two adjacent faces of the abutment-valve wings, which at the time form a portion of the limits of the expansion-chamber. Consequently there is no tendency of the valve to revolve in a reversed direction; but to prevent the possibility of such revolution one of the segmental blocks 61 is in such position that one of the rollers 59, carried by the disk 57, associated with the left abutment-valve, lies in contact with the inner face thereof, and any reverse movement is positively prevented.

Upon comparing the position of the wings 15 of the abutment-valve on the right in Fig. 8 and the position of the parts corresponding thereto in Fig. 9 it will be noted that as a piston-blade approaches one of the valves the arm 53 on the member 51 which corresponds 20 to that piston-blade will engage the roller 59 which corresponds to the wing of the abutment-valve on the right in the path of the approaching piston-blade and will impart sufficient movement to the abutment-valve to move 25 it into the position shown in Fig. 8, at which time the wing of the abutment-valve in advance of the piston will pass out of contact with the hub of the piston and will permit the passage into the space between the rear surface 30 of the abutment-wing and the front surface of the approaching piston-blade of some of the live steam from the lower expansion-chamber. As this steam is operating only upon the one 35 face of the abutment-wing, the abutment will be turned in the direction indicated by the arrow until the wing immediately behind the piston-blade moves up into a position similar to that shown at the left in Fig. 21, and the segmental block to the rear of the piston-blade 40 passing through the abutment will then come into such position that the contact of one of the rollers 59 therewith will effectively prevent any material amount of backward movement of the abutment-valve. After the piston-blade and abutment-wing have reached a 45 position similar to that shown at the left of Fig. 21 the live steam in the upper expansion-chamber of the cylinder enters the space between the piston-blade and the abutment-wing 50 immediately behind it through a small crevice between the end of the piston-blade and the surface of the abutment-wing adjacent thereto. This steam acting upon the abutment-wing behind the piston-blade tends to force the piston-blade forward and to force the abutment-wing rearward. The rearward movement of the abutment-wing is limited by contact of one of the roller 59 upon the disk 57, 55 fitted with the shaft of the abutment, as explained, and consequently the active steam is effective only in driving the blade forward and in holding the such relation thereto that the end of the piston-blade lies in contact 60 of the abutment-wing, which

at that time forms a continuation of the outer wall of the expansion-chamber.

The steam admitted through the crevice between the end of the piston-blade and the adjacent surface of the abutment-wing fills up 70 the groove at the end of the piston-blade between the two adjacent abutment-wings and the steam-port 24, which lies on that side of the cylinder, as well as all other spaces accessible. At this time the movement of the 75 valve-disk 32 will open the port 24 and will allow steam to pass from the steam-chest into the space between the piston-blade and the abutment-wing behind it. The entrance of the fresh steam from the steam-chest is thus 80 cushioned by the steam imprisoned between the piston-blade and the abutment in the manner described in the preceding paragraph, and the escape of the fresh steam around the end of the piston-blade is effectively prevented 85 by the close contact of the end of the piston-blade and the surface of the abutment-wing adjacent thereto.

From the foregoing description of the valve-operating mechanism and explanation of its mode of operation it will be seen that the initial portion only of each movement of an abutment-valve is produced by mechanical means and that the greater portion of each movement following the initial portion thereof is due to the direct action of steam upon the abutment-wings. It will also be seen that the arrangement of parts is such that live steam is allowed to pass around the end of each piston-blade as it passes through an 100 abutment-valve and to enter the space between the piston-blade and the following abutment-wing in sufficient quantity to fill the adjacent steam-port in order to cushion the entrance of steam from the steam-chest when 105 the steam-port is open and to draw the preceding abutment-wing into close contact with the end of the advancing piston, thus acting like a check-valve and preventing any escape 110 of the steam from the steam-chest around the end of the piston-blade by passing between it and the surface of the adjacent abutment-wing.

By means of the set-screw 55 and the curved slot 56 in the member 51 it is possible to adjust the position of the member 51 to correct any failure of the abutments to move in proper time relation to the piston-blade. When the piston-blades strike against the abutment-wings as the blades enter the valves, it will 115 be necessary to shift the member 51 forward in the direction of movement of the main shaft of the engine, and when the abutment-wings are moved forward too quickly it will be necessary to shift the member 51 in the 120 opposite direction.

By making the segmental block 61 adjustable toward and from the center of the disk 59 I am enabled to insure proper positioning of said blocks and abutment-valve, so that 125

the end of the piston-blade will lie in contact with the face of the adjacent abutment-wing and the said face will form a continuation of the inner surface of the wall of the expansion chamber, but at the same time avoid pressure of the abutment-wing against the end of the piston-blade, with consequent wear of the abutment-wing and piston-blade.

In order to prevent the escape of steam through the journals of the shafts of the abutment-valves and pistons in the end plates of the cylinders and valve-chambers, I provide the form of packing best shown in Fig. 10, in which is illustrated the packing of one of the shafts of an abutment-valve and which corresponds in construction to the packing of the other shafts and makes separate description thereof unnecessary.

62 is a hollow valve-stem having a projecting flange or disk inside the head or end plate of the abutment-valve chamber, said disk having an annular groove 63, which is filled with antifriction material of any suitable kind, which is fitted to a ground valve-seat in the end plate.

65 is a key provided in the shaft underneath the flange of the valve-stem 62, which allows sliding movement of the valve-stem on the shaft, but causes it to revolve with the shaft. 65^a is the gland of a stuffing-box 66, formed in the end of the hollow valve-stem 62, and 67 is a set collar keyed to the shaft and having attached thereto a coiled spring 68, which has swivel connection with the end of the gland, as shown. The gland 65^a is firmly screwed into the stuffing-box 66, so that the valve-stem 62 and gland form practically one structure. The flange of the valve-stem 62, provided with its facing of antifriction material, as already described, is held by the pressure of the steam in the abutment-valve chamber in contact with the ground valve-seat in the end plate, this contact being facilitated by the vacuum-chamber, caused by cutting away a portion of the valve-seat, as indicated at 69. The valve is kept in engagement with the seat by means of the coiled spring 68, carried by the set collar 67 and engaging with the end of the gland 65 by means of the swivel connection already mentioned, this swivel permitting the free rotation of the gland, as it is screwed into the valve, while the spring remains stationary with the set collar 67, to which it is attached. As the gland 65 and the stuffing-box revolve with the shaft and do not come into contact with anything to cause wear, a steam-tight joint will be maintained until the valve-seat in the head-plate and the antifriction-material face of the flange of the valve-stem 62 are worn out, the spring 68 and the pressure of the steam in the abutment-valve chamber being effective at all times to keep the valve in engagement with the seat.

The form of packing employed on the piston-blades and the wings of the abutment-valves is shown in Figs. 11, 12, 13, 14, 15, and 16 in detail and in general view in Fig. 2. The main portion of the packing for each of the blades of the rotating piston consists of two pieces of iron or steel of the form shown in Fig. 11, each comprising an end arm adapted to lie in the groove across the end of a wing of the abutment valve or blade of the piston, and a shorter arm which extends along the side of the said wing or blade toward the center. These members will be known as "angle-irons" 70, the long arms being designated as 71 and the shorter arms as 72. Each of the piston-blades is provided with a groove extending across the end from side to side, as indicated in Fig. 12, the groove being wide enough to permit the arms 71 of two angle-irons 70 to be laid therein side by side, as shown in Figs. 14 and 15. Grooves on the sides of the piston-blades are also provided, as shown in Fig. 12, for the reception of the shorter arms 72 of the angle-irons. These grooves are of the peculiar form best shown in Fig. 13, and the utility thereof will presently appear. Each of the arms 72 of the angle-irons, as shown in Figs. 11 and 13, is provided with a projection 73, which is inclined on its upper surface, as shown, and straight on the lower surface. The ends of the arms 72 are also inclined, as shown. In order to permit the seating of the arms 72 in the grooves provided in the ends of the piston-blades, it is of course necessary to provide triangular recesses for the projections 73, and in order to hold the arm 71 of the angle-irons in contact with the inner surface of the cylinder there is provided in the end of each of the piston-blades a recess 74, as shown in Figs. 12 and 13, which forms a seat for the plug 75, which is held in contact in the flat surface of the arm 71 of the angle-iron by means of a spring 76. (Best shown in Fig. 13.) It will be readily seen that this arrangement will insure contact of the arms 71 of the angle-irons with the inner surface of the cylinder as long as any of the material of said arms is left, thus compensating effectively for the wear of said arms by the continued operation of the engine. Now as wear of the arm 71 takes place from contact with the curved inner surface of the cylinder wear will also occur on the arm 72 from contact with the head-plates thereof, and it is desirable to provide some means to compensate therefor. Such means is found in the projections 73, already described, and the recesses of corresponding shape provided in the sides of the piston-blades. As the arms 71 are forced outward by the spring 76 to compensate for the wear of said arms, the inclined surfaces of the projections 73 will engage the correspondingly-inclined ends of the recesses in the ends of the piston-blades.

arms 72 will be forced outward into proper contact with the ends of the cylinder.

In order to insure equal rates of wear upon the arms 71 and 72, it is advantageous to make the arms 72 of the shape shown in Fig. 14, tapering toward the end nearest the shaft of the piston. By forming the arms 72 in this way the amount of metal to be worn down at any point is made proportional to the space traversed over by that portion of the arm, and consequently a uniform rate of wear is insured.

To cause the two arms 71, which lie in the groove across the end of each piston-plate, to remain at all times parallel and move outward as a single structure under the influence of the spring-pressed plug 75, it is desirable to provide each of said arms on the side adjacent to its fellow with a pin and slot, as best shown in Fig. 13. Each of said arms being thus provided, the pin on one engages with the slot provided in the other, and while the longitudinal movement of each arm 71 to permit proper contact of the arm 72 with the head-plates of the sleeve is in no wise prevented, any appreciable disalignment of the arms 71 is completely avoided. In order to keep the ends of the arms 72 in proper relation with the hub of the piston, the ends of said arms are cut on inclines, as shown in Figs. 11 and 13, and the steam-ring 77, as shown in Fig. 16, is provided with a correspondingly-inclined outer surface, which is adapted to engage with the inclined ends of the arm 72. This arrangement of the steam-ring and the arms 72 is provided in order that additional means may be provided to insure the proper degree of outward movement of the arms 71 to compensate for wear thereof and at the same time a tight contact be maintained between the surface of the steam-ring and the ends of the arm 72. The steam-ring is of course to be held in proper contact with the ends of the cylinder by any suitable means, as spring-pressed blocks, similar to those employed to keep the arms 71 in contact with the flat curved surface of the cylinder. In order that the rate of wear upon the surface of the steam-ring whose contact with the end of the cylinder may be the same as that of the arms 71 and 72 of the angle-irons, it is preferably formed with a narrow projecting rim on the face toward the end plates of the cylinder, which is of course the part which receives the wear. This rim is indicated at 78 in Fig. 2.

The packing employed on the abutment-valve wings is similar to that described in the preceding paragraphs as used on the blades of the piston, and hence it is unnecessary to describe in detail the packing for each of said valve-wings; but owing to the larger surface of the end of each of said valve-wings it is necessary to provide double sets of packing devices for each wing instead of a single set,

as employed on each piston-blade. This arrangement is clearly indicated in Fig. 2.

There have been described in the foregoing paragraphs of the specification all the essential elements of an engine constructed in accordance with my invention; but no mention has been made of the special form of valves and operating devices therefor used for controlling the direction of motion of the engine and the exhaust from the cylinders, and this while not absolutely essential to the operation of the engine is an important constructive feature, which has special utility in an engine designed as mine is. Referring to Figs. 1, 2, 18, and 19, there will be seen various parts of the said valve mechanism, which will now be described. In Fig. 2 are shown rotary valves 80, each consisting of a segmental member pivotally mounted in a chamber 81, communicating with an expansion-chamber of the cylinder and with channels 82 83 in the wall of the cylinder, of which the channels 82 lead to the low-pressure steam-chest and the channels 83 to the channels in the wall of the cylinder, as shown at 84. With the valves 81 in the position shown in Fig. 2 it will be seen that the piston will rotate in the direction shown by the arrows, and the exhaust-steam from the expansion-chambers will pass into channels 82, leading to the low-pressure steam-chest, 95 from which steam will be conducted into the low-pressure cylinder in the manner already explained, and the engine will operate as a compound engine, running in the direction which is arbitrarily called the "forward" direction; but if the valves are turned one-eighth of a revolution to the left—that is to say, in a direction contrary to the hands of a clock—the direction of motion of the piston will be reversed, though the engine will continue to act as a compound engine, for the exhaust will continue to pass into the low-pressure cylinder. If, however, the valves 80 are all rotated from the position shown in Fig. 2 one-third of a rotation to the right, the direction of movement of the piston will not be changed; but the exhaust from the cylinder instead of going into the channels leading to the low-pressure steam-chest will be thrown directly into those communicating with the channels 84 of the outer wall of the cylinder, and the engine will no longer act as a compound engine.

In order to impart movement to the valves 80, as above described, I provide rods 85, as shown in Fig. 1, each of which is connected to two of the valves 80 and which is connected at its upper end by means of a link with a bell-crank lever 86. The bell-crank levers 86, of which there are two at each end of the engine, though only one is shown in Fig. 1, are rigidly mounted on rods 87, supported in brackets on the cylinders. Movement is imparted to the entire system of valves by the reciprocating movement of a rod 88, connect-

ed at its ends with two of the bell-cranks and operated by the lever 89, which has a pin-and-slot connection therewith, as shown.

The valve-operating mechanism just described is that employed in connection with both of the cylinders of the engine and the movement of the valves of both cylinders is simultaneous.

The valves used in the low-pressure cylinder are similar in some respects to those of the high-pressure cylinder; but it is obvious that it is unnecessary for each expansion-chamber of the low-pressure cylinder to communicate with the channels leading to a steam-chest, for the reason that after steam has been used in the low-pressure cylinder the only further use to which it may be put is that of supplying heat to the walls of the cylinders to prevent condensation of steam within the cylinder, and consequent loss of energy.

The arrangement of the passages from the expansion-chamber of the low-pressure cylinder to the channels in the walls thereof is substantially as shown in Fig. 21, and the valves are of the same form as those illustrated in Fig. 2. The rocking of the valves in their seats serves merely to control the direction of the movement of the piston in the low-pressure cylinder and has no effect upon the character of the engine.

In the engine shown in Fig. 1 the governor employed is one of the ordinary ball type and is not in some respects so suitable for an engine of the type to which this invention pertains as that shown in Fig. 3 and already described at length. Consequently the description of the form of governor shown in Fig. 1 has been reserved as a modification that may be employed, if desired.

In the form of governor shown in Fig. 1 I make use of a pair of pivoted arms 90, mounted at the top of a rotary spindle 91 and provided at their lower ends with weights or balls 92. The spindle 91 is hollow, as usual, and has 45 extending upward therethrough a vertical governor-rod 94, mounted for vertical movement in the hollow spindle and connected with the arms 90 by means of links 95. Rotation is imparted to the hollow spindle from 50 a positively-driven shaft 96 by means of bevel-gears 97, supported within a frame 98, in the upper portion of which the spindle is journaled. The rod 94 extends downward from the bottom of the frame 98 and is pivotally connected at its lower end with a link 99, at the lower end of which is pivotally mounted a block 100. The block 100 is slidably mounted in a groove 101 in an arm 102, which is rigidly attached to a transverse shaft 103, which may 60 be supported in any suitable form of bearings. (Not shown.) At one end of the arm 102 is pivotally mounted a link 104, which is connected at its lower end with a rod 105, which is vertically movable in a guideway formed 65 in the upper portion of the wall of the low-

pressure steam-chest and in the bottom of a frame 105, on the top of which a frame 98 is supported. The rod 105 is connected, by means of a link 106, with one arm of a bell-crank 107, the other arm of which has attached thereto a ring 108, encircling a grooved collar 109. The collar 109 has projecting from one side thereof an arm 110, which carries a stud that engages an oblique slot 111, formed in the hub of the counter-disk of the low-pressure cylinder. The collar 109 is feathered to the main shaft of the engine, and the counter-disks in the two steam-chests are connected by means of a sleeve 112, so that when the collar 109 is moved longitudinally of the main shaft of the engine the two counter-disks will be advanced ahead of the shaft or moved in the opposite direction, according to the direction of movement of the grooved collar.

Associated with the block 100 is a grooved block 113, which is held at right angles to the groove 101 in the arm 102, and on a shaft 114, which is disposed in alinement with the shaft 103, is rigidly secured a disk 115, which has a stud 116, that engages with the groove in the block 113. At the end of the shaft 114 opposite the disk 115 is a small segmental gear 117, which is adapted to engage with a short rack 118, formed on the upper surface of the longitudinal rod 88, and rigidly secured upon the shaft 114, midway between its ends, is an arm 119, having on the end thereof a weight 120, which lies normally in the position shown in solid lines in Fig. 1 and which will be raised past the vertical by the engagement of the rack 118 with the segmental gear 117 whenever the rod 88 is shifted to reverse the engine. When the weight 120 passes the point immediately above the shaft 114, gravity will cause it to descend to the position shown in dotted lines in Fig. 1, and the engagement of the stud 116 with the block 113 will shift it to the end of the arm 102 opposite that at which it is normally located. Consequently the outward movement of the balls of the governor which previously caused a downward movement of the link 103 will, when the weight 120 occupies the position shown by dotted lines in Fig. 1, cause an upward movement of the link 104 and will produce a similar reversal of the movement of the bell-crank 107 and the shrouded collar 109. This reversal of the movements of the bell-crank and collar is for the purpose of adapting the movement of the cut-off disks to the reversed direction of movement of the engine resulting from the movement of the rod 88.

In Figs. 20 and 21 are illustrated a rotary engine employing abutment valves and pistons of the form already described, but having only a single cylinder and with the packing devices omitted for the sake of clearness. In this form of engine the construction of the cylinder is, as already stated, the same as that employed as a low-pressure cylinder in the

compound engine already described; but the valves 80^a, indicated therein, are of somewhat different form from those employed with the low-pressure cylinder of a compound engine, 5 for the reason that the movements necessary in the valves of the compound engine are not necessary here. In other respects the cylinder of the simple rotary engine and the means for properly timing and adjusting the movements of the abutment valves and pistons are 10 the same as those employed in connection with the low-pressure cylinder of the compound engine. Hence detailed description thereof by specific reference to the different parts, as indicated in the drawings, appears to be unnecessary.

The operation of an engine constructed in accordance with my invention has been brought out in piecemeal in the description of the 20 different sets of mechanisms entering into the construction of the engine with sufficient degree of clearness to render further statement thereof unnecessary at this point; but I wish to draw attention to certain advantages possessed by an engine constructed in accordance 25 with my invention, which are not found, so far as I am aware, in rotary engines as hitherto constructed. A cardinal feature of my invention lies in the abutment-valves, which consist 30 of three wings, as described, said wings being substantially of the same width at their extremities as the openings between the wings and having their faces cut on arcs of the same radius as the expansion-chambers of the cylinder in connection with which they are used. By means of abutment-valves constructed in 35 this manner and supported on shafts so situated that the faces of the valves may be brought into alinement with the wall of the expansion-chamber of the cylinder it is possible to completely eliminate all clearance when the end 40 of a piston-blade passes from the valve-chamber into contact with the wall of the expansion-chamber of the cylinder and at the same time to do away with the sudden movement 45 of the abutment-valve necessary in engines having abutment-valves whose faces are curved in the manner described, but having a larger number of wings. This sudden movement referred to is clearly illustrated in Patent 50 No. 610,191; and it is obvious with an abutment-valve constructed as shown in that patent such movement is necessary in order to cause the passage of the piston-blade through the valve with a minimum loss of energy by the escape of steam around the end 55 of the piston-blade. In the construction which I use it will be seen that the end of a wing of an abutment-valve remains in contact 60 with the hub of the piston during the expansion of the steam in the expansion-chamber and during the passage of the piston-blade through the valve, thus completely preventing all backward travel of the steam and also 65 making it possible for the abutment-valve to

begin its forward movement immediately after the piston-blade passes into contact with the wall of the cylinder after going through the valve, to move gradually forward until the succeeding piston-blade is almost into the 70 valve, when the next wing of the abutment is brought rapidly into position behind the piston-blade, as already explained in a preceding paragraph.

By means of the disk valves for controlling 75 the admission of steam into the cylinders and the counter-disks controlled by the governors, as already described, the speed of the engine is controlled effectively, and the admission of steam into the cylinders is automatically adjusted to the load on the engine in a very simple manner. On account of the way in which the disk valves are keyed to the shaft said valves are made to operate equally well to regulate the admission of steam when the engine is going in a normally forward direction 80 and when reversed.

The other advantages possessed by an engine constructed in accordance with my invention have been suggested in connection with the 90 description of the different sets of mechanism embodied therein, and attention will not be again directed thereto.

Having described the nature and operation 95 of my invention, what I claim as new, and desire to secure by Letters Patent, is—

1. The combination in a rotary steam-engine, of a cylinder having a plurality of expansion-chambers, rotary abutment-valves separating said chambers, each of the valve-wings having rounded outer ends of extended width for contact with the body of the piston thereby to permit movement of the abutment-valve in advance of the approach of a piston-blade and the wings being separated by substantially V-shaped recesses, a piston having a plurality of blades adapted to enter the abutment-recesses, means for imparting initial movement to the abutment-valves, and means for stopping the valves in position to permit the passage of the piston-blades without clearance.

2. The combination in a rotary steam-engine, of a cylinder having a plurality of expansion-chambers, and rotatably-mounted 115 abutment-valves separating said expansion-chambers, each of said valves having three wings whose ends each comprise an arc of sixty degrees and whose faces are curved on the same radius as said expansion-chambers 120 thereby to permit preliminary movement of an abutment-valve in advance of the approach of a piston-blade.

3. The combination in a rotary steam-engine, of a cylinder containing a plurality of 125 expansion-chambers, a plurality of rotatably-mounted abutment-valves separating said chambers, each of said rotatably-mounted abutment-valves having a plurality of wings, and a piston having a blade adapted to traverse 130

759,571

said expansion-chambers, each of the wings of said abutment-valves having its faces curved on the same radius as said expansion-chambers and its end adapted to contact with the hub 5 of said piston during the passage of a piston-blade through the valve the ends of the wings being of a width approximately equal to the width of the space between said wings thereby to permit preliminary movement of, the 10 abutment-valves immediately after a piston-blade is passed therethrough.

4. The combination in a rotary steam-engine, of a cylinder having a plurality of expansion-chambers, a plurality of rotatably-mounted abutment-valves separating said chambers, and a piston mounted to rotate within said cylinder having a blade adapted to traverse said expansion-chambers and pass through said abutment-valves, each of said 15 abutment-valves having a plurality of wings each of which has its faces concavely curved on the same radius as the expansion-chambers, and the piston-blade being convexly curved upon each of its faces on the same radius as said 20 expansion-chambers and abutment-wings.

5. The combination in a rotary steam-engine, of a cylinder having a plurality of expansion-chambers, a piston mounted to rotate in said cylinder and having blades adapted to 25 traverse said expansion-chambers, a plurality of abutment-valves separating said expansion-chambers, and mechanism operated by said piston to impart an initial movement to said abutment-valves whenever the piston-blade 30 passes through a valve, said mechanism comprising a member carried by the piston-shaft and having a plurality of arms and disks mounted on the shafts of the abutment-valves and provided with pins adapted to be engaged 35 by the arms of said member.

6. The combination in a rotary steam-engine, of a cylinder provided with a plurality of expansion-chambers, a shaft extending through said cylinder, a rotatable piston rigidly mounted thereon and having a plurality of blades, rotary abutment-valves separating said expansion-chambers and adapted to permit the passage of the piston-blades there-through, and mechanism for imparting initial 45 movement to said abutment-valves to permit the passage of the piston-blades, comprising a disk mounted on the piston-shaft and having a plurality of arms, disks associated with the abutment-valves and a plurality of pins, 50 bearing antifriction-rollers provided on said disks and adapted for engagement with the arms on the first-mentioned disk.

7. The combination in a rotary steam-engine, of a cylinder having a plurality of expansion-chambers, a piston mounted for rotation within said cylinder, rotary abutment-valves separating said chambers, means for imparting initial movement to said abutment-valves, comprising a member mounted for rotation with the piston and having a plurality 65

of arms, and disks mounted for rotation with said abutment-valves, each having a plurality of pins adapted for engagement with said arms, and means for preventing backward movement of said abutment-valves, comprising a disk mounted for rotation with said piston and having a plurality of adjustable segments adapted to engage with the pins upon the disks associated with the abutment-valves. 70

8. The combination with a rotary piston-blade or abutment-valve wing, of packing comprising metallic bars bent at right angles and having one portion thereof disposed in a groove in the end of said plate or wing and the other portion thereof disposed in grooves in 80 the sides of said wing or blade, said side portions of the packing-bars being tapered at their terminals to make the rate of wear of the surface thereof uniform, and means for moving said bars outward from the end and sides 85 of said blade or wing to compensate for wear of the surface of said bars.

9. The combination with a rotary piston-blade or abutment-valve wing, of packing comprising metallic bars bent at an angle and having one portion thereof seated in a groove in the end of said blade or wing and the other portion seated in grooves in the sides of said 90 blade or wing, a spring-pressed plug in the end of said blade or wing adapted to hold the 95 end portions of said bars outward, and inward projections provided on the side portions of said bars and having sloping surfaces adapted to engage reversely-inclined walls of recesses provided in the sides of said wing or blade 100 and to force said side portions of said packing-bars outward from said wing or blade.

10. The combination with a rotary piston comprising a hub and blades, of packing devices comprising angular bars disposed in 105 grooves across the ends and sides of said blades, the side portions of said bars terminating in beveled ends, and a steam-ring mounted in an annular groove in the hub of said piston and having a beveled periphery adapted to engage 110 the beveled ends of the side portions of said packing-bars so that the outward movement of the steam-ring to compensate for wear on the surface thereof will cause corresponding outward movement of said packing-bars. 115

11. The combination with a cylinder-head in a rotary engine, of a shaft mounted to rotate in bearings provided in said cylinder-head, a valve-seat ground in said cylinder-head, a valve mounted to rotate with the said shaft 120 and engaging said seat and having a stuffing-box formed in the stem thereof, a gland screwed into said stuffing-box, and a spring engaging said gland to hold the valve in position.

12. The combination in a compound rotary steam-engine having high and low pressure cylinders, of high and low pressure steam-chests disposed between said cylinders, and the high-pressure steam-chest being entirely surrounded by the low-pressure steam-chest. 125 130

13. A rotary steam-engine having the walls of the cylinders and steam-chests channeled to form a steam-jacket, and valved exhaust-ports for the passage of exhaust-steam from the cylinder to said jacket thereby to maintain said walls at a high temperature and prevent the condensation of steam in the steam chests or cylinders. 35
14. In a rotary engine, a cylinder, a revolvable piston having blades, a revolvable abutment having a plurality of wings, means for imparting initial movement to the abutment in advance of the approach of a piston-blade, said abutment being movable to operable position by the pressure of the actuating fluid, and means for limiting the movement of the abutment under pressure. 40
15. The combination in a steam-engine, of a cylinder, a piston, a hollow shaft connected to the piston, a ported cylinder-head, a revolvable valve-disk mounted on the shaft and having ports that are successively brought into alignment with the cylinder-head ports, a counter-disk movable to regulate the area of the ports of the valve-disk, a governor-shaft extending through the hollow shaft and having at its inner end a crank-arm extending through an opening in the piston-shaft and secured to the counter-shaft, and a centrifugal governor connected to the outer end of the governor-shaft and serving to rock the same to alter the position of the counter-disk, substantially as specified. 45
16. The combination in a rotary steam-engine, of a cylinder having a plurality of expansion-chambers separated by rotating abutment-valves, a piston having a plurality of blades mounted to rotate in said expansion-chambers, steam-ports in the cylinder end adjacent to the end of the abutment-valves, and steam-inlet valves coöperating with said ports and so connected with the piston and the abutment-valves that steam will be admitted at intervals timed to enable the steam to impart movement to the abutment-valves. 50
17. The combination in a rotary engine, of a cylinder having a plurality of expansion-chambers separated by rotating abutment-valves, a piston having a plurality of blades mounted to rotate in said expansion-chambers, steam-ports in the cylinder end adjacent to the abutment-valves, steam-inlet valves coöperating with said ports, connections between said piston and said steam-inlet valves to impart movement to said valves, and mechanism associated with the piston for imparting initial movement to the abutment-valves, the final movement of the abutment-valves being caused by the direct action of steam acting between the piston-blades and the wings of the abutment-valves. 55

In testimony that I claim the foregoing as my own I have hereto affixed my signature in the presence of two witnesses.
